Primary Examiner — Jennifer Rivard*Assistant Examiner* — April Rivas(74) *Attorney, Agent, or Firm* — Kilpatrick Townsend & Stockton LLP(57) **CLAIM**

The ornamental design for a combined liquid cooling cold plate and vapor chamber, as shown and described.

DESCRIPTION

FIG. 1 is a top perspective view of a combined liquid cooling cold plate and vapor chamber showing our new design; FIG. 2 is a top perspective disassembled view corresponding to FIG. 1;

FIG. 3 is a left side elevational view thereof;

FIG. 4 a right side elevational view thereof;

FIG. 5 is a rear elevational view thereof;

FIG. 6 is a front elevational view thereof;

FIG. 7 is a top plan view thereof; and,

FIG. 8 is a bottom plan view thereof.

The broken lines illustrate portions of the combined liquid cooling cold plate and vapor chamber and form no part of the claimed design.

1 Claim, 8 Drawing Sheets(56)
